Application February 23, 1952, Serial No. 272,999

8 Claims. (Cl. 324—33)

This invention relates to high vacuum and more particularly to pressure gauges for measuring absolute pressure from atmospheric down to pressures on the order of 10^{-6} mm. Hg abs. The present invention is primarily concerned with improvements in gauges of the type described in U. S. Patent No. 2,497,213, issued February 14, 1950 to J. R. O. Downing.

The Downing gauge comprises a radioactive source whose rate of emission of ionizing agents is substantially constant and is substantially independent of temperature and electrical field therearound. This radioactive material is positioned to radiate ionizing agents into a space between two electrodes so as to ionize gas molecules which are within an ionization chamber holding the two electrodes.

In a preferred embodiment of the Downing gauge the source of ionizing agents is an alpha particle emitter, such as radium, or a beta particle emitter, such as strontium 90. The invention will be more particularly described in connection with the use of such charged particles as ionizing agents, although the general principles are clearly broadly applicable to other types of ionizing agents. The ionization within the chamber is measured by collecting ions produced therein and amplifying and indicating the ion current so collected. The ionization current bears a direct relationship to the composition and absolute pressure of the gas within the gauge. Over a substantial range of pressures this relationship is that of simple proportionality. Departures from this proportional or linear relationship between gas pressure and ionization current are encountered at still higher pressures. This departure results from the combined effect of two principal causes. First, the number of ion pairs (i. e., one positive ion and one electron) produced by an ionizing particle in traversing a given mass of gas varies significantly as the ionizing particle approaches the end of its range. Secondly, at high pressures the concentrations of positive ions and electrons, produced by the ionizing particle, become sufficiently great so that a significantly large portion of these positive ions and electrons recombine before reaching the collecting electrodes. It is, of course, necessary that the positive ion and a corresponding electron reach their respective electrodes in order to appear as ionization current. Ions recombined in the gas do not contribute to this current.

In designing an ionization chamber for some specific range of operating pressures as, for example, from about 10 mm. to atmospheric pressure, the above considerations may be applied as follows: It is desired that the ion current, which is collected by the electrodes, be taken only from those ion pairs which are produced by ionizing particles which have traveled considerably less than their mean residual range. By "mean residual range" is meant the mean range (in units of length) of the ionizing particles after they enter the gas whose pressure is to be measured. This range depends somewhat on the composition of the gas and, naturally, is inversely proportional to the pressure of the gas. For example, in

2

the case of alpha particles emanating from radium, this "mean residual range" is the mean range, at the pressure of the gas, of the alpha particles after they have passed through the film of rhodium which is preferably used to confine the decay products (e. g., radon) of radium. Another consideration is that the distance between the two electrodes in the ionization chamber should be as small as possible so as to discourage recombination of the ion pairs. In practice, the above two considerations are amply provided for if the mean effective limits of the ionization chamber are maintained less than the "mean residual range" of the ionizing particles at the maximum pressure to be measured. Since the electrodes are within this ionization chamber, the distance between electrodes is considerably less than this particular "mean residual range."

Since, at absolute pressure on the order of 1000 mm., the mean residual range of alpha particles, for example, is relatively short (of the order of one inch), a very small effective ionization chamber is required for linear readings in the atmospheric pressure range. On the other hand, the measurement of very low pressures cannot be readily achieved with a very small ionization chamber, since the ratio of "dark current" to positive ion currents is excessively large. This "dark current" is due, at least in part, to alpha particle bombardment of the positive ion collector electrode. At low pressures, the positive ion current generated in the gas is very small, since it is a direct function of the pressure and the limits of the ionization chamber, as expressed (for air) by the equation $I=5.25 \times 10^{-18} LNP$, wherein I is ionization current in amperes, P is the pressure to be measured in millimeters, N represents the useful activity of the radioactive material in alpha particles per second directed into the ionization chamber, and L represents the mean distance in centimeters between the source of alpha particles and the effective limits of the ionization chamber.

While it is possible to use a dual ionization chamber with two separate sources of ionizing agent activity, and suitable switching means for obtaining linear readings over a wide pressure range, this dual system has the disadvantage that two separate sources of ionizing agent (e. g., radium) must be employed. Since the radioactive materials utilized in these Downing gauges constitute an appreciable amount of the total cost of such gauges, the use of two radium plaques, for example, in a single gauge is disadvantageous from the standpoint of economics and health.

Accordingly, a principal object of the present invention is to provide an improved pressure gauge of the Downing type which has a linear response over a wide range of pressures from atmospheric pressures to pressures on the order of 10^{-6} mm. Hg abs.

Another object of the present invention is to provide such a gauge which employs only a single source of ionizing agent activity.

Still another object of the invention is to provide a gauge of the above type which includes a small ionization chamber within a larger chamber, this smaller ionization chamber being electrically isolated from the large chamber to prevent migration of positive ions from one chamber to the other.

Other objects of the invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following

detailed description taken in connection with the accompanying drawings wherein:

Fig. 1 is a diagrammatic, schematic diagram showing one preferred embodiment of the invention; and

Fig. 2 is an enlarged fragmentary view of a portion of Fig. 1.

In the present invention there is provided a first electrode defining a relatively large ionization chamber, and a first collector electrode within this large chamber. Means are included for maintaining a potential difference between the two electrodes so that positive ions are collected by one of the electrodes, and negative particles (ions and electrons) are collected by the other of the electrodes. In a preferred embodiment of the invention the source of ionizing agent activity is an alpha particle emitter, such as radium, which will create positive ions as a direct function of pressure. The first electrode (which defines the ionization chamber) is maintained at a potential V_1 , and a second electrode is maintained at a potential V_2 ; the potential V_2 being negative relative to V_1 in order that the second electrode may collect the positive ions. Without intent to limit the invention it will be particularly described in connection with the use of such an alpha emitter as the source of ionizing agent activity and with the various electrodes arranged so that the collection of positive ions is used to measure pressure.

The gauge also includes a third electrode which defines a second ionization chamber, this second chamber being relatively small with respect to the first ionization chamber. This second ionization chamber is also provided with a collector electrode, the fourth electrode in the gauge. The source of ionizing agent activity (e. g., radium) is positioned so that the alpha particles emitted therefrom traverse both the large and small ionization chambers. In a preferred embodiment of the invention the radium is positioned within, or closely adjacent, the small ionization chamber and its alpha particles traverse the small ionization chamber before entering the large ionization chamber. The alpha particles, then pass through the electrode defining the small ionization chamber, and then traverse the larger ionization chamber.

With this arrangement of elements, the collection of positive ions is used to indicate the pressure within the gauge. The electrode which defines the smaller ionization chamber is permeable to alpha particles and is maintained at a potential V_3 (preferably equal to V_1) to prevent migration of positive ions from one chamber to the other. In this connection it is particularly important that migration of positive ions from the larger to the smaller chamber be avoided when the smaller chamber is being used to measure relatively high pressures.

Referring now to Figs. 1 and 2, there is shown one preferred embodiment of the invention which is particularly adapted for use with a radium plaque which serves as a source of ionizing agent activity. In these figures, the gauge comprises a housing 10 which is sufficiently rugged to withstand evacuation. This housing or casing 10 preferably serves as an electrode (having the potential V_1) and defines therewithin an ionization chamber 12. Within the chamber 12 is a collector electrode 14 arranged to be maintained at a potential V_2 more negative than V_1 so as to collect the positive ions. A second ionization-chamber-defining electrode 16 is positioned within the chamber 12, this second electrode 16 being at a potential V_3 which preferably equals V_1 . Within the ionization chamber 20 defined by the second electrode 16 there is provided another positive-ion collector electrode 18 which is maintained at a potential V_4 , preferably equal to V_2 . As illustrated, the electrode 18 preferably comprises a plurality of hoop-shaped members which serve as a grid or porous casing, permitting passage of high energy alpha particles but serving to repel positive ions approaching the grid 16. As illustrated, particularly in Fig. 2, part of the smaller ionization chamber 20 is defined by a radium plaque 22 which is supported on a

pair of conducting strips 23, these conducting strips 23 being secured to the housing 10. This radium plaque 22 is preferably of the type described in the above mentioned Downing patent and is arranged so that it is in equilibrium with its immediate decay products.

The two positive-ion collector electrodes 14 and 18 are preferably supported by insulators 24 and 26, respectively, and are also connected to electrical leads 25 and 27, respectively.

As seen in Fig. 1, the electrical circuit for measuring the positive-ion currents collected by the two electrodes 14 and 18 comprises an amplifier, generally indicated at 30. This amplifier includes a meter 32 preferably calibrated directly in increments of pressure, and is arranged to give a direct indication of the absolute pressure within the chamber 12. The amplifier 30 is preferably of the type described by N. F. Moody in Rev. Sci. Instruments 22, No. 4, 236 (1951). In conjunction with this amplifier circuit, there is preferably provided a range-shifting mechanism for reading low pressures, intermediate pressures and high pressures. This range-shifting mechanism preferably includes a resistance network comprising resistances R-1, R-2, R-3 and R-4 and a plurality of thermally operated relays RY-1, RY-2 and RY-3. In one preferred embodiment, the various resistances have the following values:

$$R-1=1,000 \text{ megohms}$$

$$R-2=10,000 \text{ megohms}$$

$$R-3=100,000 \text{ megohms}$$

$$R-4=1,000 \text{ megohms}$$

The relays RY-1, RY-2 and RY-3 are connected to pressure range selector buttons B₁, B₂, and B₃, respectively, so that the appropriate range can be selected by the operator. A zero set selector button B₀ is also provided, this selector button being arranged to close relays RY-1 and RY-3, although the circuitry for accomplishing this is not shown.

The above resistance network, comprising resistances R-1, R-2, R-3, and R-4, serves as a particularly desirable arrangement for selectively feeding, to a single amplifier, equivalent voltages corresponding to the widely different ionization currents from the two ion collectors. At low gas pressures, the ionization current from collector 14 alone is used, the current from collector 18 being grounded through RY-1. The ionization current from collector 14 is relatively small and the high resistance R-3 serves as the input resistance to the amplifier. This arrangement of input resistors serves for a hundred-fold range of pressure, say P_1 to P_2 . For still higher pressures, as P_2 to P_3 , the relay RY-2 is closed and R-1 serves as the input resistance to the amplifier. By this means, a range of four decades (i. e., $P_3=P_1 \times 10^4$) is available. If the linear range of the large chamber 12 and its collector electrode 14 covers more than this pressure range of four decades, additional lower valued resistors and associated relays (not shown) can be placed in parallel with R-1 and RY-2 across the input to the amplifier. At still higher gas pressures, as P_3 to P_4 , the ionization current from collector 18 alone is used, the ionization current collected by collector 14 being grounded by relay RY-3; relays RY-1 and RY-2 being open. The ionization current from collector 18 is relatively large and the relatively low resistance R-4 serves as the input resistance.

Since at the high pressures above P_4 the ion current collected by electrode 18 is inherently large, for conveniently constructed sizes of chamber 20, it is necessary that the input resistance by which electrode 18 is connected to ground be not too high. This is achieved, as shown, by the use of resistor R-4, with resistors R-3 and R-2 acting as a voltage divider in a three-resistor circuit of satisfactorily low net input resistance.

There are several advantages to the use of the above arrangement. First, the number of components connected to the amplifier input is reduced to a minimum, thus pre-

serving the extremely high-resistance leakage path necessary for proper operation. Second, by the same token, the input shunt capacitance is kept low, permitting rapid response to pressure variations. Third, the use of thermally operated relays is made possible, whereby stray magnetic fields deleterious to the amplifier operation may be avoided.

The insulators 24 and 26, shown in considerable detail in Fig. 2, are preferably provided with guard rings 40 and secondary insulators 42 so as to provide a very low effective leakage current for these insulators. These guard rings 40 are preferably connected to an electrical lead 44 which is at about the same potential as the potentials V_2 and V_4 of the electrical leads 25 and 27. This guard ring 40 thus serves to shield the two output leads 25 and 27 from the positive potential on the housing 10.

The circuit diagram of Fig. 1 also shows a preferred relationship of the potentials V_1 and V_3 to the potential of the nearby conducting objects considered as "ground." As seen, V_1 and V_3 are preferably connected directly to ground to eliminate shock hazard and the possibility of malfunction from accidental grounding of the chamber 10. As is apparent from Fig. 2 the position of the radium plaque 22 is such that alpha particles emanating therefrom pass through the small ionization chamber 20 defined by the grid electrode 16. The alpha particles pass between the gaps in the electrode 16 and then enter the large ionization chamber 12. For measuring high pressures the positive ions created within the small ionization chamber 20 are collected by electrode 18. The small size of the chamber 20 permits linear response of the gauge at high pressures due to the fact that the dimensions are less than the mean residual range of the alpha particles, even at pressures on the order of 1,000 mm. Hg abs. In order to maintain this linearity, the distance between the source of alpha particles and the limits of the ionization chamber 20 are preferably kept below about 0.25 centimeters. The fact that the electrode 16 is at the potential V_3 substantially prevents the migration of positive ions, generated outside of the ionization chamber 20, from entering the ionization chamber 20 and thus destroying the linearity of the pressure measurement.

When the pressures become below about 10 mm. Hg abs., the collector electrode 14, in the large ionization chamber 12 is used for collecting the positive ions generated therewithin by the alpha particles which pass through the openings in the electrode 16.

In the operation of the gauge illustrated in Fig. 1 it is connected to a vacuum system by means of a suitable fitting 28. If the vacuum system is at atmospheric pressure, the selector button B_3 is pushed so that only the positive ion current collected by the collector 18 is fed to the amplifier. When the pressure in the vacuum system has been reduced to below about 10 mm. Hg abs., the selector buttons B_1 and B_2 are actuated so that now only the positive ion current collected by the collector 14 is fed to the amplifier. The fact that both relays RY-1 and RY-2 are closed, however, permits reading of relatively high ionization currents. When the pressure drops below about 0.10 mm. Hg abs., the selector button B_2 is deenergized so that very small ionization currents, which correspond to the low pressures, can be read. When it is desired to obtain a zero-set reading, selector button B_0 is actuated, this serving to close the relays RY-1 and RY-3 and preventing the feeding of any positive ion currents into the amplifier.

While the invention has been described particularly with respect to a preferred modification thereof, numerous alternative embodiments may be employed without departing from the invention. For example, the small chamber 20 may be positioned outside of the large ionization chamber 12 in an auxiliary housing fastened to housing 10. Additionally, the housing 10 may be made longer and narrower, if desired, and the small ionization chamber may be formed in one end of this long narrow housing.

Equally, it is not essential that the radium plaque 22 be positioned so that it actually defines one side of the small ionization chamber. However, it is desired that the small ionization chamber and the radium plaque be so related that the alpha particles emitted from the radium plaque pass through the small ionization chamber before passing into the large ionization chamber. Additionally, the plaque can separate the two ionization chambers so that radiation emitted from one side of the plaque enters one chamber while radiation from the other side of the plaque enters the other chamber. This arrangement is less desired since a radium plaque having equal emissivity from both sides is more difficult to prepare. Equally, the electrode 16 which defines the small ionization chamber may take a number of different shapes. It can be a wire mesh or any suitable arrangement which will not unduly hinder the passage of alpha particles therethrough. If desired, electrode 16 can be at a more positive potential than the housing 10. Equally, the housing 10 may be a grid-like casing positioned within a second, more rugged, vacuum-tight housing. However, this is not necessary with the particular circuit shown, and merely adds to the insulating problems.

While radium has been described as a preferred source of ionizing agent activity, numerous other materials such as beta ray emitters (e. g., strontium 90) or gamma ray emitters (e. g., filtered radiation from radium) may be employed. Gamma ray emitters are least desirable since their ionization efficiency is least and their health hazard is greatest. In those cases where the ionization agents are other than alpha particles, suitable modifications in the circuitry may be employed. For example, where beta rays are the ionization agents their use may require different input resistors since the ionization produced by beta rays is less than the ionization produced by alpha particles.

While it is preferred that positive ions be collected to indicate pressure, negative ions can be equally collected by suitable reversal of polarity in the gauge and by modifying the amplifier.

Since certain changes may be made in the above apparatus without departing from the scope of the invention herein involved, it is intended that all matter contained in the above description, or shown in the accompanying drawing, shall be interpreted as illustrative and not in a limiting sense.

What is claimed is:

1. A gas pressure gauge operable at pressures above atmospheric pressure without damage thereto and comprising an electrode which defines an ionization chamber, an ion collector within the ionization chamber, means for maintaining said ion collector at a potential different than said electrode, a second electrode defining a second and smaller ionization chamber which communicates with said first ionization chamber, a second ion collector positioned in said smaller ionization chamber, means for maintaining a potential difference between said second electrode and said second ion collector, said second electrode being maintained at a potential which will repulse ions of the type collected by said second ion collector to prevent migration of said ions into said smaller ionization chamber, a single radioactive source whose rate of emission of ionizing agents is substantially constant and substantially independent of temperature and electric field therearound, said second electrode being substantially permeable to said ionizing agents, said radioactive source being positioned to radiate ionizing agents into said two ionization chambers, means conductively connected to said collectors for amplifying current created by the collection of ions at either of said collectors, and means connected to the output of the amplifying means for indicating the magnitude of said amplified currents and thus the gas pressure within said ionization chambers.
2. A gas pressure gauge operable at pressures above atmospheric pressure without damage thereto and com-

prising an electrode which defines an ionization chamber, an ion collector within the ionization chamber, means for maintaining said ion collector at a potential different than said electrode, a second electrode defining a second and smaller ionization chamber which communicates with said first ionization chamber, a second ion collector positioned in said smaller ionization chamber, means for maintaining a potential difference between said second electrode and said second ion collector, said second electrode being maintained at a potential which will repulse ions of the type collected by said second ion collector to prevent migration of said ions into said smaller ionization chamber, a single radioactive source whose rate of emission of ionizing agents is substantially constant and substantially independent of temperature and electric field therearound, said second electrode being substantially permeable to said ionizing agents, said radioactive source being positioned to radiate ionizing agents into said two ionization chambers, the limits of said smaller ionization chamber being less than the mean residual range of said ionizing agents at the maximum pressure to be measured, means conductively connected to said collectors for amplifying current created by ions collected at either of said collectors, and means connected to the output of the amplifying means for indicating the magnitude of said amplified currents and thus the gas pressure within said ionization chambers.

3. A gas pressure gauge operable at pressures above atmospheric pressure without damage thereto and comprising an electrode which defines an ionization chamber, an ion collector within the ionization chamber, means for maintaining said ion collector at a potential which is negative with respect to said electrode, a second electrode defining a second and smaller ionization chamber which communicates with said first ionization chamber, a second ion collector positioned in said smaller ionization chamber, means for maintaining a potential difference between said second electrode and said second ion collector so that said second ion collector collects positive ions, said second electrode being maintained positive with respect to said first collector so as to prevent migration of positive ions into said smaller ionization chamber, a single radioactive source whose rate of emission of ionizing agents is substantially constant and substantially independent of temperature and electric field therearound, said second electrode being substantially permeable to said ionizing agents, said radioactive source being positioned to radiate ionizing agents into said two ionization chambers, means conductively connected to said collectors for amplifying current created by the positive ions collected at either of said collectors, and means connected to the output of the amplifying means for indicating the magnitude of said amplified currents and thus the gas pressure within said ionization chambers.

4. A gas pressure gauge operable at pressures above atmospheric pressure without damage thereto and comprising an electrode which defines an ionization chamber, an ion collector within the ionization chamber, means for maintaining said ion collector at a potential which is negative with respect to said electrode, a second electrode defining a second and smaller ionization chamber which communicates with said first ionization chamber, a second ion collector positioned in said smaller ionization chamber, means for maintaining a potential difference between said second electrode and said second ion collector so that said second ion collector collects positive ions, said second electrode being maintained positive with respect to said first collector so as to prevent migration of positive ions into said smaller ionization chamber, a source of ionizing agents comprising radium positioned to radiate alpha particles into said two ionization chambers, said second electrode being substantially permeable to alpha particles, means conductively connected to said collectors for amplifying current created by the positive ions collected at either of said collectors, and means connected

to the output of the amplifying means for indicating the magnitude of said amplified currents and thus the gas pressure within said ionization chambers.

5. A gas pressure gauge operable at pressures above atmospheric pressure without damage thereto and comprising an electrode which defines an ionization chamber, an ion collector within the ionization chamber, means for maintaining said ion collector at a potential which is negative with respect to said electrode, a grid within said ionization chamber, said grid defining a second and smaller ionization chamber, a second ion collector positioned in said smaller ionization chamber, means for maintaining a potential difference between said grid and said second ion collector so that said second ion collector collects positive ions, a source of ionizing agents comprising radium positioned to radiate alpha particles into said two ionization chambers, said grid being constructed so as not to interfere with the majority of alpha particles emitted from said source, and means for maintaining said grid at a potential substantially preventing passage of positive ions into said smaller ionization chamber, said radium being positioned so that some of the alpha particles emitted therefrom pass through said smaller ionization chamber and into said larger ionization chamber, means conductively connected to said collectors for amplifying current created by the positive ions collected at either of said collectors, and means connected to the output of the amplifying means for indicating the magnitude of said amplified currents and thus the gas pressure within said ionization chamber.

6. A gas pressure gauge operable at pressures above atmospheric pressure without damage thereto and comprising an electrode which defines an ionization chamber, an ion collector within the ionization chamber, means for maintaining said ion collector at a potential which is negative with respect to said electrode, a second electrode defining a second and smaller ionization chamber which communicates with said first ionization chamber, a second ion collector positioned in said smaller ionization chamber, means for maintaining a potential difference between said second electrode and said second ion collector so that said second ion collector collects positive ions, at least a portion of said second electrode comprising a grid-like member separating said two ionization chambers, said grid-like member being maintained at a potential which is positive with respect to said two collector electrodes, said grid-like member permitting equalization of pressure within said two ionization chambers, a source of ionizing agents comprising radium positioned to radiate alpha particles into said two ionization chambers, means conductively connected to said collectors for amplifying current created by the positive ions collected at either of said collectors, and means connected to the output of the amplifying means for indicating the magnitude of said amplified currents and thus the gas pressure within said ionization chambers.

7. The pressure gauge of claim 1 wherein said means for amplifying current created by collection of ions comprises a resistance network for selectively feeding, to a single amplifier, equivalent voltages corresponding to ionization currents of widely different amplitudes from the two collectors, said resistance network being arranged so that at low gas pressures the relatively small ionization current from the first ion collector develops a voltage across a relatively high input resistance while at high gas pressures the relatively large ionization current from the second ion collector develops an equivalent voltage across a relatively low input resistance, and a voltage divider between said low input resistance and said amplifier, at least part of said voltage divider comprising said high input resistance.

8. Apparatus for measuring the pressure of a gas by measuring ionization produced in the gas, said apparatus comprising two ion collectors and means conductively connected to said collectors for amplifying ion currents

collected by either of said collectors, said amplifying means comprising a resistance network for selectively feeding, to a single amplifier, equivalent voltages corresponding to ionization currents of widely different amplitudes from the two collectors, said resistance network being arranged so that at low gas pressures the relatively small ionization current from the first ion collector develops a voltage across a relatively high input resistance while at high gas pressures the relatively large ionization current from the second ion collector develops an equivalent voltage across a relatively low input resistance, a voltage divider between said low input resistance and said amplifier, at least part of said voltage divider comprising said high input resistance, and means con-

nected to the output of the amplifier for indicating the magnitude of said amplified currents and thus the gas pressure to be measured.
